UNITED STATES PATENT OFFICE.

LOUIS GODDU, OF WINCHESTER, ASSIGNOR TO JAMES W. BROOKS, PRINCIPAL TRUSTEE, OF CAMBRIDGE, AND FRANK F. STANLEY, ASSOCIATE TRUSTEE, OF SWAMPSCOTT, MASSACHUSETTS.

NAILING-MACHINE.

SPECIFICATION forming part of Letters Patent No. 440,805, dated November 18, 1890.

Application filed January 21, 1890. Serial No. 337,595. (No model.)

To all whom it may concern:

Be it known that I, LOUIS GODDU, of Winchester, county of Middlesex, State of Massachusetts, have invented an Improvement in 5 Screw-Inserting Machines, of which the following description, in connection with the accompanying drawings, is a specification, like letters on the drawings representing like parts.

10. This invention is intended as an improvement upon that class of machine represented in United States Patent No. 171,610, dated December 28, 1875, the said machine being adapted to insert a screw-threaded wire into 15 a sole or "stock," as it is called, held between a nose at the lower end of a rising and falling head and the top of a horn, the said head and horn having an oscillating motion about a vertical pivot to effect the feeding of the 20 material.

In the machine described in the patent referred to the head is automatically lifted a defined distance above the surface of the stock after the wire has been inserted and the 25 shoe fed and the wire cut off, the head being lifted from the stock and moved laterally back to its starting-point, ready to again descend upon the stock on the horn prior to inserting a second fastening, and so on. The 30 lifting of the head in the machine described in the said patent is accomplished through a cam on the main shaft of the machine supported in the said head, the said cam acting upon a lever pivoted at its inner end on the 35 head, the opposite end of the said lever being attached by a connecting-rod to a movable carrier or yoke provided with pivoted clamping-blocks, which blocks co-operate with a fixed vertically-placed pin located on the post 40 of the machine. The carrier or yoke referred to receives through its inner end a rod which is connected to the head, the said rod having a shoulder near its lower end to act against the upper side of the said yoke, a spring 45 rounding the lower end of the said rod acting against the under side of the said yoke, so that whenever the head descends the shoulder on the said rod acts upon the yoke and keeps it in substantially horizontal position, so that

the clamps of the yoke may move freely in a 50 vertical direction on the said pin; but whenever the head was to be lifted the cam on the shaft referred to, by acting on the lever, also before referred to, moved the link and tipped the yoke out of horizontal position, thus causing 55 the blocks to tightly clamp the said pin. After the blocks were moved to clamp the said pin, the said cam in its further rotation acted against the said lever, the outer end of which then rested upon the link or connecting-rod held rigidly, thus causing the head to rise from the stock. This mechanism, fully 60 described in the patent referred to, has in practice been found at times not to operate properly because of failure of the clamps to 65 properly hold fast upon the pin, and in such event the head fails to be lifted sufficiently to properly release the stock and enable the head to be swung back into its normal or starting position.

The object of this present invention is to 70 provide means by which to positively lift the head, as will be hereinafter described, and control the pawl, which receives the weight of the head when being lifted.

75 My invention consists in a screw-inserting machine containing the following instrumentalities—viz., a vertically and laterally movable head, a shaft therein having a cam, a lever actuated thereby, a connecting-rod and pawl-carrying slide having a pawl D³, and a ratchet-toothed plate adapted to be engaged by the 80 said pawl, and a cast-off wedge and means to move said wedge to control the engagement of the said pawl with the said ratchet-toothed 85 plate, substantially as will be described.

Figure 1 is a left-hand side elevation of a sufficient portion of a nailing-machine embodying my invention to enable the same to 90 be understood. Fig. 2 is a sectional detail to the left of the line y, Fig. 1.

Referring to the drawings, the horn A, the head E, carrying the usual spindle D, having suitable wire-feeding rolls H at its lower end, the cam or main shaft I, having a worm-wheel G², the lever V, and the means for rotating the said main shaft are and may be all 95 as in the patent referred to. The spindle D

will be actuated as in the said patent from a friction-pulley x^2 , fully described therein, and under the control of a treadle R.

In this my present invention the parts added to the machine before referred to derive their motion from a cam B, which occupies the position on the said shaft which is occupied by a cam marked V³ in the said patent, the cam B having, however, a differently-shaped cam-groove and having a peripheral throw, the point of which commences at x^2 and ends at x^3 .

The column C of the machine has a lug C', which receives a stand C², having an attached ratchet-toothed plate C³, the said stand also having suitable openings or bearings for a pawl-carrying slide D², it having a pawl D³, which is acted upon by a pin D⁴, which is normally pressed outwardly by a spring D⁵, herein shown as made adjustable in the said pawl-carrying slide D² by a suitable screw D⁶. The stand referred to has also suitable guideways to receive a controlling-bar E², having an attached cast-off wedge b, the said wedge being herein shown as attached to the said bar by a screw b', a rod extended from the upper end of the said bar and constituting part of it being jointed at b² to a lever b³, pivoted on a pin b⁴, constituting the fulcrum for the lever V. The lever b³ has, as shown, a roller which is acted upon by the periphery of the cam B to depress and hold down the said bar and cast-off wedge during a little more than one-half a rotation of the cam B.

The pawl-carrying slide D² is joined by a link or connecting-rod d' with a block d², pivoted upon the outer end of the lever V, the connection of the said block with the said lever being preferably made adjustable, the said lever V having a roller or other stud, as d³, to enter the cam-groove d⁴, cut in one side of the cam B, the shape of the said groove being fully shown in the drawings. This rod d' is preferably made adjustable as to its length so as to compensate for wear of the parts, the adjustment of the rod d' toward and from the fulcrum of the lever V regulating the extent of rising and falling movement of the head. The extremity of the said rod is preferably made spherical, as represented in Fig. 2, at the lower end of the said rod. The pawl-carrying slide has a projection or ear e², upon which rests the lower end of a spiral spring e³, the upper end of the said spiral spring acting upon an adjustable collar e⁴ to normally keep the roll of the arm b³ against the periphery of the cam B.

Referring to the drawings, especially Fig. 2, the parts are shown in the position they will occupy while the spindle is being rotated to insert one end of the screw-wire into the stock and the head and horn are being swung with the shoe to feed the same with relation to the usual gage f, which is fixed upon the column, and against which the operator presses the edge of the sole, and in Fig. 2 it will be noticed that the pawl D³ is acted upon by the cast-

off wedge, and therefore the pawl does not then engage a tooth of the fixed ratchet-plate C³. This pawl is kept out of engagement with the teeth of the said ratchet-plate until the head has received its feeding movement and is in position to be lifted from the stock, at which time the heel x³ of the cam B passes beyond the roll of the arm b³, so that the bar E² rises and carries the cast-off wedge above the lower end of the pawl D³, so that the said pawl engages one of the teeth of the ratchet-plate C³. The engagement of the pawl with the ratchet-plate having been effected, the cam B in its further rotation, by acting upon the roll d³ of the lever V, causes the head E to be elevated, as provided for in the patent referred to, it being obvious that the said head must at such time be lifted by the cam B in its rotation, for the pawl-carrying slide is fixed and cannot descend, so the head must rise. This lifting of the head from the stock puts the head in condition to be swung around, as provided for in the said patent, to its starting-point, the operator at such time holding the edge of the shoe against the gage referred to, so that the horn of the usual nose of the machine travels backward over the shoe. As soon as the head arrives at its starting-point, the cam B in its further rotation, owing to the shape of the groove therein, permits the head to descend and the usual nose to rest upon the surface of the stock, and just at this time a slight further movement of the cam, acting upon the roller or other stud d³, lifts the lever V and the connecting-rod and pawl-carrying slide just enough to unseat the pawl D from the ratchet-tooth then engaged by it, and at the same time, or immediately thereafter, the point x² of the throw portion of the cam B strikes the roll on the arm b³, thus depressing the bar E, causing the cast-off wedge to act against the pawl D and keep it out of engagement with the said ratchet-plate, the said wedge continuing to hold the said pawl out of engagement with the teeth of the said ratchet-plate until the head is to be again lifted, when the pawl will be again engaged with the ratchet-plate, as before stated.

The pawl in operation engages one or the other of the teeth of the ratchet-plate, according to the thickness of the stock, and the fulcrum-pin b⁴ for the levers b³ and V rises and falls with the head, so that the head is lifted always a certain distance from the stock on the horn, no matter what its thickness, and the head is always adapted to act upon stock of any varying thickness. The outward movement of the pawl D³, after the same has been unseated from the ratchet-teeth of the plate, as described, by the cast-off wedge, prevents the breaking of the said teeth, and the said cast-off wedge, when acting against the said pawl, also holds it so that the operator with his foot on the treadle R may raise and lower the head in order to enable him to put a shoe upon the horn or remove a shoe from the horn

without the pawl clicking upon or touching the ratchet-teeth, for it will be remembered that the levers b^3 and V rise and fall with the head.

5 It would not be practicable to knock the pawl out from engagement with the teeth of the ratchet-plate without first unseating the pawl by an upward motion thereof, for if the pawl were not so unseated the teeth would be 10 broken off and destroyed, because the weight of the head sustained by the pawl is very great.

I claim—

A screw-inserting machine containing the following instrumentalities, viz: a vertically 15 and laterally movable head, a shaft therein

having a cam, a lever actuated thereby, a connecting-rod, a pawl-carrying slide having a pawl D^3 , a ratchet-toothed plate adapted to be engaged by the said pawl, and a cast-off wedge and means to move it to control the engagement of the said pawl with the said ratchet-toothed plate, substantially as described. 20

In testimony whereof I have signed my name to this specification in the presence of two subscribing witnesses.

LOUIS GODDU.
